UNITED STATES PATENT OFFICE.

JOHN WOOSTER, OF DOWAGIAC, MICHIGAN.

BOX.

1,111,120.

Specification of Letters Patent. Patented Sept. 22, 1914.

Application filed June 22, 1912. Serial No. 705,248.

To all whom it may concern:

Be it known that I, JOHN WOOSTER, a citizen of the United States, residing at the city of Dowagiac, county of Cass, and State 5 of Michigan, have invented certain new and useful Improvements in Boxes, of which the following is a specification.

This invention relates to improvements in boxes.

- 10 The main objects of this invention are,— First, to provide an improved box adapted for use as a berry box or the like, which may be packed and shipped in the knockdown and quickly and easily assembled by the 15 user. Second, to provide an improved box embodying these advantages, which may be made of comparatively light material such as light paper-board or the like, and set up without stapling or gluing, and one which 20 when set up, is strong and rigid and not likely to collapse. Third, to provide an improved box adapted for use as a berry box or the like, which may be formed in one piece and easily assembled or set up by the user. 25 Further objects, and objects relating to structural details, will definitely appear from the detailed description to follow.

I accomplish the objects of my invention by the devices and means described in the 30 following specification.

The invention is clearly defined and pointed out in the claims.

A structure which is a preferred embodiment of my invention is clearly illustrated in 35 the accompanying drawing, forming a part of this specification, in which:

Figure I is a perspective view of a structure embodying the features of my invention. Fig. II is a vertical section taken on a 40 line corresponding to line 2—2 of Fig. I. Fig. III is a detail horizontal section taken on a line corresponding to line 3—3 of Fig. I. Fig. IV is an end elevation looking from the left of Fig. II, portions of the wall being broken away to show structural details. Fig. V is a plan view of a blank of my 45 improved box.

In the drawing, similar reference characters refer to similar parts throughout the 50 several views, and the sectional views are taken looking in the direction of the little arrows at the ends of the section lines.

Referring to the drawing, the side walls and bottom of my improved box are preferably formed of the integral blank shown in 55 Fig. V. This blank has side wall portions 1,

2, 3, 4, bottom portion 5, bottom extensions or side wall members 6 and 7, and a connection member 8 for the inner bottom extension 6 to the inner wall portion 4. The outer wall portion 1 is provided with a flap 9 and the outer bottom extension or member 7 is provided with a flap 10, terminating in a tongue 11. The outer bottom extension 7 is provided with tongues 12 on its edges. 60 The side wall portion 3 is provided with a slot 13 for the tongue 11. The wall portions 2 and 4 are provided with vertical slots 14 for the tongues 12.

The blank is scored transversely on the 70 lines 17 to facilitate folding. The connecting member 8 is diagonally scored at 15. The diagonal scoring 15 of the connecting member 8 extends from the folding line 17 between the bottom extension 6 and the 75 member 8 at one edge to a notch 18 in the other edge.

The bottom portion of the blank from the notch is of greater width than the side wall portion of the blank, as clearly shown in the 80 drawing, the length of the bottom portion of the blank being approximately the length of the side wall and the width the length of the end walls. The boxes may be so proportioned that this notch is not necessary, and 85 may be relatively deeper and shallower. I have, in the accompanying drawing, shown the box proportioned about the same as an ordinary berry box.

In setting up the box, the side walls are 90 folded to position with the flap 9 on the inside. The connecting member 8 is folded diagonally on the line 15, the inner bottom extension being folded over the upper edge of the wall 1, to engage the flap 9 thereof, 95 thus locking the sides together. See Figs. I and III. The flap 10 is folded over the opposite wall 3 and its tongue 11 engaged in the slot 13 thereof, and the tongues 12 engaged in the slots 14. This supports the 100 bottom and retains the side walls in their erected position.

My improved box when erected is very rigid and secure, and may be easily and quickly set up without the aid of tools. The 105 box when set up is braced and secured so that it may be formed of quite light material and still is very strong and rigid.

I have illustrated and described my improvements as embodied in a berry box, although adapted for various other purposes. When formed of paper-board and adapted 110

for use as a berry box, the inner side of the box is preferably paraffined or formed of waterproof material which can be done while the material is in the flat or before 5 making the blanks.

Having thus described my invention, what I claim as new and desire to secure by Letters Patent is:

- 10 1. A knockdown or collapsible box formed of a blank consisting of a straight strip having a portion thereof wider than the rest of said strip, the narrow portion of said strip being scored transversely to provide side wall portions, and an end flap on the outer end of the narrow portion of said blank, the wide portion of said strip being scored transversely to provide a bottom portion and bottom extensions on either side thereof, an end flap on the outer end of said 15 wide portion of the strip, and a connecting member between the inner bottom extension and the inner side wall portion, the said connecting member being scored diagonally from the top of the inner side wall extension to the inner end of the narrow portion of the strip, the outer bottom extension being provided with tongues on its edges, the outer end flap of said extension being also provided with a tongue, a slot in one of the side 20 wall portions adapted to receive the tongue of said flap, slots in the adjacent side wall portions adapted to receive the tongues on the edges of said outer bottom extension, said narrow portion of the strip being folded 25 along the transverse scorings to form the side walls of the box, said connecting member being folded along its diagonal scoring, the inner bottom extension being folded over 30
- 35

one of the side walls, the outer bottom extension being folded over the opposite side wall with the tongue of said flap in engagement with the slot in said side wall, all co-acting substantially as described for the purpose specified.

- 40 2. A knockdown box formed of a blank comprising a straight strip scored transversely to form side wall portions, an end flap for the outer side wall portion of the blank, a bottom portion with bottom extensions at each side thereof, an end flap for the outer bottom extension, and a connecting member between the inner bottom extension and the inner side wall portion, said member being scored diagonally from the top of the inner bottom extension to the bottom edge of said member, the outer bottom extension being provided with tongues on its edges, the flap of said extensions being also provided with a tongue, said connecting member being folded on the diagonal scoring, the inner bottom extension being folded over one of the side walls engaging said first named end flap, the outer bottom extension flap being folded over one of the side walls, said wall having a slot for the tongue of said flap, the adjacent side walls being slotted to receive the tongues on the edges of said outer bottom extension.

In witness whereof, I have hereunto set my hand and seal in the presence of two witnesses.

JOHN WOOSTER. [L. S.]
